UNITED STATES PATENT OFFICE.

FREDERICK B. LEOPOLD, OF EVANSTON, ILLINOIS.

WASHTROUGH FOR FILTERS.

No. 829,113.

Specification of Letters Patent.

Patented Aug. 21, 1906.

Application filed October 27, 1905. Serial No. 284,730.

To all whom it may concern:

Be it known that I, FREDERICK B. LEOPOLD, a resident of Evanston, in the county of Cook and State of Illinois, have invented a new and useful Improvement in Washtroughs for Filters; and I do hereby declare the following to be a full, clear, and exact description thereof.

My invention relates to washtroughs for filters.

The object of my invention is to provide a trough of such character that during the washing operation the velocity of the upward flow of the wash-water will be reduced and practically freed from the eddies and counter-currents which are present in connection with the washtroughs heretofore employed and which have a tendency to retain the suspended matter longer on the filter-bed, and so require a longer application of the wash-water to remove it, while at the same time the velocity of the water in its upward course acted to carry a quantity of sand with it into the trough.

To these ends my invention comprises, generally stated, a trough having bulging or protruding walls, forming a contracted mouth, which act to gently divert the upwardly-rising water and compel the same to travel in a substantially horizontal course before flowing into said trough.

To enable others skilled in the art to make and use my invention, I will describe the same more fully, referring to the accompanying drawings, in which—

Figure 1 is a plan view of a filter with my invention applied thereto. Fig. 2 is a section on line 2 2, Fig. 1. Fig. 3 is a cross-section. Fig. 4 is an enlarged cross-section of trough.

Like numerals indicate like parts in each.

In the drawings the numeral 2 designates a section of a sand filtration plant of ordinary construction having the inlet-pipe 3 for raw water, the sand bed 4, the air-pipe 5, the air-manifold 6, the water-manifold 7, the clear-water pipe 8, and the wash-water conduit 9.

Arranged centrally of the filter and extending longitudinally thereof is the gutter 10, which carries off the dirty water and scum removed in the cleaning operation. Connected to this central gutter 10 are the troughs 11, which extend from the side walls of the filter to said gutter. These troughs 55 may be formed of metal plates 12 of suitable thickness, and the said plates are bent to

form bulging or protruding walls, forming inclined faces 13 and 14. Each trough may be formed of two plates connected by the metal straps 15 at suitable intervals and leaving a small opening 20 between said plates for the purpose fully hereinafter set forth. This trough may be made of concrete, wood, or any other suitable material. Angles 16 secure the trough to the side walls of the filter 60 and to the gutter-wall 17. Angle-bars 18, extending from the side walls to the wall 17, further brace and support said trough.

When it is desired to wash the filter-bed, the wash-water is admitted from below in the ordinary manner, and as the water rises in the filter it agitates and washes the same. As the water rises it is directed by the inclined faces 13 of the trough and travels up said faces without creating eddies or counter-currents, so that the suspended matter rises quickly and without interference. Furthermore, owing to the faces 14 the water before entering the trough is compelled to follow a substantially horizontal course, so that the sand contained therein has an opportunity to settle before being carried into the trough. The space above the faces 14 being protected from the upward agitation or flow of the water is not disturbed to any extent, so that the water is comparatively quiet at this point, and as a consequence the grains of sand, which are heavier than the water, have opportunity to settle. As they settle they fall upon the faces 14. The water when it reaches 75 the overflow is substantially free from any sand lifted by the agitation of the water. When the washing operation ceases, as the water subsides it flows down the faces 14 and washes any sand deposited thereon back into 80 the filter-bed.

To further guard against the passage of sand into the waste, I employ the opening 20, which will permit any sand entering the trough to find its way back into the filter-bed.

What I claim is—

1. A washtrough for filters having bulging or protruding walls forming inclined faces and a contracted mouth.

2. A washtrough for filters having a projecting top portion extending outwardly from the mouth of said trough, whereby the water before entering said trough travels in a horizontal or substantially horizontal course.

3. A washtrough for filters having an inclined top portion extending from the mouth

of said trough, whereby the water before entering said trough travels in a horizontal or substantially horizontal course.

4. A washtrough for filters having outwardly-projecting top portions extending from the mouth of said trough at both sides thereof, whereby the water before entering said trough travels in a horizontal or substantially horizontal course.

10 5. A washtrough for filters having inclined top portions extending from the mouth of said trough at both sides thereof, whereby the water before entering said trough travels in a horizontal or substantially horizontal course.

15 6. A washtrough for filters having upwardly and outwardly inclined faces extend-

ing from the bottom of said trough to a point and inwardly and upwardly inclined faces extending from said point to the mouth of 20 said trough.

7. A washtrough for filters having an opening in the bottom thereof leading back into the filter.

8. A washtrough for filters comprising 25 metal plates connected together with a slight intervening space between their lower edges.

In testimony whereof I, the said FREDERICK B. LEOPOLD, have hereunto set my hand.

FREDERICK B. LEOPOLD.
